DISKLIKE PLAYTHING

Paul W. Garbo, Freeport, N. Y.

Application August 28, 1947, Serial No. 771,049

4 Claims. (Cl. 273—106)

1

This invention relates to a plaything which, more particularly, comprises a resilient body having a disk-like shape and being adapted for whirling or throwing through the air.

In the field of sports and exercise, balls hold a prominent position. To hurl a ball to and fro between players is an enjoyable pastime involving healthful exercise by the players. As known, an overhand throw develops certain muscles of the player while an underhand throw develops others.

A primary object of this invention is to provide means for enjoyable exercise calling into play muscles and physical movements which are not involved in ordinary ball playing.

A related object is to provide a plaything for developing gracefulness and suppleness in players through exercise.

A further object is to provide a device for the amusement of young and old alike.

Other objects of my invention will be apparent from the description which follows.

I have found that an object having a resilient surface and a shape substantially like that of a disk is a versatile plaything of wide appeal.

For a clearer understanding of my invention, reference is now made to the appended drawings of which:

Figure 1 is a plan view of one form of disk illustrative of my invention;

Figure 2 shows the disk of Figure 1 partly as an elevation and partly as a section taken along the line 2—2 of Figure 1;

Figure 3 is a plan view of a modified embodiment of the invention;

Figure 4 represents a partial section taken along the line 4—4 of Figure 3;

Figure 5 is a partially sectioned view, similar to Figure 4, presenting still another embodiment of the invention;

Figure 6 is a plan view of another form of disk, part of the upper face being broken away to show the inner construction; and

Figure 7 is a sectional view of the disk of Figure 6 taken along the line 7—7.

The disk 10 of Figures 1 and 2 has flat faces 11 and rounded or beveled edges 12. A smaller disk 13 of a stiffening material such as plastic, wood or aluminum forms the core of the finished disk 10. The resilient covering of the disk 10 consists of two layers 14 of a material like foamed or sponge rubber suitably bonded to opposite sides of the stiffening member 13 and a flat ring 15 of the springy material fitted around the edge of disk 13 and bonded thereto as well as to the layers 14 along the interfaces 16.

2

The disk 20 of Figures 3 and 4 comprises two substantially flat resilient faces 21 having central openings 22 with rounded edges 23 thereabout and rounded edges 24 along the periphery of the disk 20. Two disks 25 of transparent plastic or the like are held in spaced relation so that balls 26 may move freely therebetween when the disk 20 is hurled or rolled. A flat ring 27 of foamed rubber has an inner tongue-like portion or flange 28 which fits between the transparent disks 25 and thus keeps them spaced for the movement of the confined balls 26. As shown, the disk 20 is made up of two flat rings 29 of foamed rubber or similar soft and springy material attached by adhesive to the rigid core of two disks 25 and to the flat ring 27 along the interfaces 30. The outer surface of the rubbery ring 27 is provided with corrugations 31.

Figure 5 shows a modified form of disk of the type presented in Figures 3 and 4. In this instance, the disk 40 comprises two resilient rings 41 having concentric corrugations 42 on their outer faces. The central openings 43 in the two rings 41 reveal the rigid core which is made up of a cup-like member 44 of a transparent plastic, e. g., polystyrene or cellulose acetate, and a disk 45 of the same plastic acting as the cover or lid of the cup-like member 44. The space within the core portion is partially filled with a liquid 46 such as water containing an attractive dye. The lid 45 is hermetically sealed to the rim 47 of the cup-like member 44. A resilient flat ring 48 surrounds the liquid-containing core portion and is united to the rings 41 along the interfaces 49.

The disk 50 of Figures 6 and 7 has convex faces 51 and an undulating periphery 52. A ring 53 of a stiffening material, e. g., metal or plastic, is embedded in disk 50. In the particular form represented by Figures 6 and 7, disk 50 is made by cementing or otherwise bonding together two elements of resilient material having convex faces 51 and rounded edges 54; the two elements are joined together along their flat faces 55. As shown, the elements may be formed with cavities 56 in the flat faces 55 so as to reduce the weight of the finished disk 50. The cavities 56 which provide gas cells or pockets within disk 50 also function to increase the softness and resilience of the disk.

A more specific example illustrative of my invention will be given in terms of a disk of the type shown in Figures 1 and 2. The stiffening core was a disk of cellulose acetate, measuring 5½ inches in diameter and ¼ inch in thickness. This core was sandwiched between two ¾-inch layers of foamed rubber and was encircled by

a flat ring of the same rubber. The resilient covering over the plastic core was held together by adhesive. The finished disk was 8 inches in diameter and weighed 11 ounces. It could be hurled through the air by one player with the same easy swinging motion reminiscent of an ancient discus-thrower and could be caught while in flight by another player without difficulty or fear of injury. It could be bounced off a wall or floor by whirling the disk in such manner that the flat portion of its edge struck the surface from which it was to rebound. As in billiards, the disk could be thrown with "English" or spun to alter the direction of bounce when the disk contacted a fixed surface. Children enjoyed rolling it along the ground to one another at high speed without hurting themselves. In short, the disk was found an amusing and healthful plaything in the home, on the lawn, at the beach or at any other recreational place.

The dimensions of the disk may be varied as desired but for throw-and-catch exercise I find that disks of about 6 to 10 inches in diameter and about 1 to 2 inches in thickness are more desirable. Also, the weight may be varied at will but for safety the disk is usually made to weigh less than 1 pound.

While the several illustrative embodiments of my invention have been described as comprising an outer surface or casing of foamed rubber (natural or synthetic) which is the preferred resilient material, other resilient constructions may be employed. For instance, the disk may have a sheet covering of a suitable material such as leather, rubber, fabric or flexible plastic film, like the covering on a baseball, and cotton wadding, animal hair, feathers, wool, glass fibers, steel wool, or a similar stuffing material may fill the sheet covering to form the disk and provide a soft, springy surface.

The simplified forms of the disks shown in Figures 1, 2, 6 and 7 are generally preferred by adults, while children usually favor disks of the types represented by Figures 3, 4 and 5 having the additional attraction of moving parts which give pleasing visual and sound effects when the disks are rolled or hurled.

Those skilled in the art will visualize many

other modifications and variations of the playing disks of my invention. For instance, instead of forming a disk by cementing together two or more elements, the disk may be molded as a unitary product. It is, therefore, intended that all matter contained in the foregoing description shall be interpreted as illustrative and not in a limiting sense.

What I claim is:

- 10 1. A plaything in substantially the form of a disk with substantially symmetrical opposite faces adapted for hurling and catching exercise, which comprises a soft resilient outer casing made of foamed rubber measuring about six to ten inches 15 in diameter and about one to two inches in thickness, and a stiffening inner rigid core, said inner core occupying only a minor proportion of the volumetric extent of said plaything and said outer casing providing a solid, thick rim about said 20 inner core.
2. The plaything of claim 1 wherein said inner core is made of transparent material and said outer casing is disposed around said inner core to permit light to pass through the central portion 25 of said inner core.
3. The plaything of claim 2 wherein said inner core is hollow and contains a movable body.
4. The plaything of claim 3 wherein said movable body is liquid.

30

PAUL W. GARBO.
